WILLIS LAMONT ASH, OF LANSING, MICHIGAN.

SPARK-PLUG.

No. 895,225.

Specification of Letters Patent.

Patented Aug. 4, 1903.

Application filed October 11, 1905. Serial No. 282,244.

To all whom it may concern:

Be it known that I, WILLIS LAMONT ASH, a citizen of the United States, residing and having my post-office address at Lansing, 5 in the county of Ingham and State of Michigan, have invented certain new and useful Improvements in Spark-Plugs, of which the following is a specification.

My invention relates to spark plugs for 10 gasolene or gas engines, and its object is to prevent leakage through the plug, diminish liability of breaking the porcelain insulator, and diminish the liability of injury to the electrode or the insulator by the heat and 15 shock of the explosion. I attain these objects by the construction shown in the accompanying drawings, in which

Figure 1 is a longitudinal section of my spark plug complete. Fig. 2 is a partial 20 longitudinal section of a modified form on a larger scale. Figs. 3 and 4 show different methods of constructing the head of the electrode.

The body P of my spark plug is of the ordinary construction and is adapted to receive 25 the porcelain insulator A, said insulator being retained in position by the shoulders H and I, which are compressed between the washer K and the bushing J, as shown in 30 Fig. 1. This washer K is preferably of copper, and acts as a packing to prevent any leakage around the insulator. The upper extremity B of the insulator is of a conical shape, and the entire insulator is pierced 35 longitudinally with an opening about $\frac{1}{8}$ th of an inch in diameter. Ordinarily it is not advisable or safe to use an insulator with so large an opening as stated above, but the peculiar construction of the electrode employed by me makes it possible to do this 40 with perfect safety, and great advantage in point of durability and ease of assembly and repair. The electrode D passes freely through the opening C. On the upper extremity is either formed or attached an enlarged cap E, to which is secured the sparking point Q. Between this cap and the extremity of the insulator B is placed a cushion or ring of asbestos or similar material which 45 seats in an annular cup shaped recess formed in the inner face of the cap E, one wall of which is defined by the electrode D and the other wall of which is defined by an inwardly extending flange. This cushion serves not 50 only as an elastic cushion to protect the point of the insulator from the shock of the

explosion, but also as a packing to prevent leakage through the opening C around the electrode D in which use the nose-pointed end of the head B bears against the adjacent 60 face of the cushion within the confines of the said flange. The lower extremity of the electrode D is threaded and passes through a cap L which is held by a lock nut O bearing frictionally thereagainst; a dish shaped annular spring washer M fits inside the cap around the electrode D, and between it and the body A of the insulator as shown in Fig. 1 to further relieve the shock of the discharge and allow for expansion and contraction of the electrode D.

As shown in Figs. 2, 3, and 4, the head of my electrode may be constructed in various ways. Thus it may be formed integrally on the body as shown in Fig. 3, or screwed to it 75 as shown in Fig. 4. At present I much prefer to form the head in the form of a cup as shown in Figs. 3 and 4, but if desired it may be constructed in the manner shown in Fig. 2, namely, with a flat lower surface; in which 80 ease the elastic cushion R is preferably retained in position by being embedded in a slight depression on the extremity B of the insulator.

This construction, as already stated, enables me to use a large electrode. This is of 85 material advantage for several reasons. It conducts away the heat more rapidly from the point, thus diminishing the danger of breaking the porcelain. It enables me to secure the electrode in place with screw threads instead of cement, as is customary, thus securing a more perfect protection against 90 leakage, less liability to destruction by shock, which often produces leakage by breaking 95 the cement, and great ease of repairing or replacing the electrode or insulator in case of injury. The enlarged cap combined with the elastic cushion and the large electrode rod serves to a great extent to protect the 100 point of the insulator from the heat, and also from the shock of the explosion. Besides, their large size and close contact with the body of the insulator serve to conduct the heat rapidly away from the point, and thus 105 add greatly to its durability.

Claims.

1. A spark plug embodying an insulator, an electrode having threaded ends extending through an opening provided therefor in 110 said insulator, a cap having a closed end and formed with a threaded opening receiving

one end of said electrode, a sparking point projecting beyond the outer face of said closed end, said cap at its open end being formed with an annular-cup shaped recess which merges into said threaded opening of the cap whereby a downwardly hanging protecting flange is formed an elastic cushion seating in the said recess, a second cap having an opening through which the opposite end of said electrode passes, an annular dish shaped spring washer perforated and receiving said insulator and disposed between the last named end of the insulator and the end of said second cap, and a securing nut on the 15 electrode bearing against said second cap.

2. A spark plug embodying an insulator, an electrode passed axially through said insulator, said electrode being provided at one end thereof with an enlarged head bearing

against the end of said insulator and having 20 a sparking point, said electrode having its other end threaded, a securing cap on the threaded end of said electrode, said cap having an annular flange receiving and surrounding the adjacent end portion of said insulator 25 and an annular dish shaped spring cushioning washer surrounding said electrode and received within said flange, said washer being interposed between and lying in contact with the body of said cap and the adjacent end 30 face of said insulator.

In testimony whereof I affix my signature in presence of two witnesses.

WILLIS LAMONT ASH.
